UNITED STATES PATENT OFFICE.

ALFRED J. GILLESPIE, OF ATLANTIC, IOWA, ASSIGNOR TO THE U. S. STANDARD VOTING MACHINE COMPANY, OF ROCHESTER AND JAMESTOWN, NEW YORK, A CORPORATION OF NEW YORK.

INDORSING DEVICE FOR VOTING-MACHINES.

933,428.

Specification of Letters Patent.

Patented Sept. 7, 1909.

Application filed June 17, 1908. Serial No. 438,888.

To all whom it may concern:

Be it known that I, ALFRED J. GILLESPIE, a citizen of the United States, residing at Atlantic, in the county of Cass and State of 5 Iowa, have invented certain new and useful Improvements in Indorsing Devices for Voting-Machines, of which the following is a specification.

This invention relates to indorsed candidates on voting machines whereby, when a candidate has been nominated by two or more parties for the same office and his name appears two or more times on the machine for that office in a multi-candidate group, the 10 counters belonging to said candidate may be coupled together for simultaneous action whereby one vote and only one vote can be counted for such candidate by any one voter.

The invention will be more readily understood by reference to the accompanying drawings forming a part of this specification.

Figure 1 is an elevation of two counter channels as viewed from the back of the 25 machine, with my improved indorsing bar placed between them. Fig. 2 is a view taken on section line of 2, 2 in Fig. 1 looking in the direction of the arrow. Fig. 3 is a section or line 3, 3 in Fig. 2 looking in the direction of the arrow.

In the drawings and specifications like numerals refer to like parts.

In the accompanying drawings I have illustrated certain details of the machine 35 such as are described in several recent patents such as Nos. 847,416 and 849,001, issued to W. J. Lausterer.

In Fig. 1 reference numerals 4 and 5 refer to the bottom and top plates of the 40 movable counter frame. Fastened to said counter frame are the parallel counter channels 6—6, in each of which counter channels is carried all of the counters that belong to its particular office line in the machine. These 45 counters are substantially of the same type as are described in my Patent 761,218, and are driven or operated by the pallet bar substantially the same as is described in said patent. Each counter 7 has at its right hand 50 side a pallet bar 8 or counter actuator, and the numeral wheels of the counter are all carried on the single shaft. On the end of each of these shafts and outside of the coun-

ter channel is carried the knurled wheel 9 by means of which the counter may be reset. 55 In the outer end of the pallet bar is punched the small hole 10.

Between the counter channels I insert an indorsing bar 11, which bar is slightly longer than the counter channels. At suitable intervals therein I provide pin holes 12 to which may be fitted links 13, such as are shown in Figs. 3 and 2. This link consists of a narrow piece of sheet metal curved down at its outer end and bearing therein 65 a pin 14 which pin is designed to engage with the hole 10 at the outer end of the pallet bar. Any two counters in the same office line that belong to the same candidate should have their pallet bars connected to 70 the indorsing bar 11, by the links 13. When the indorsed counters have been so connected up a vote registered on any one of the counters will be registered alike on all of these counters in the following way. If the 75 pallet bar 15 in Fig. 2 is directly operated, the upper end of the indorsing bar 11 will be drawn forward toward the plate 5 of the counter frame. When the upper end of bar 11 comes in contact with bar 5 it will cease 80 moving forward at its upper end. The parts are so designed, however, that this will occur before the pallet bar 15 has reached the end of its stroke and as the pallet bar 15 continues toward the end of its stroke, the 85 bar 11 will begin to swing with its contact with the bar 5 as a center and the lower end of the bar will be drawn forward thereby until the pallet bar 15 has completed its forward stroke. These terms are used relatively, it 90 being understood that the operated pallet bars stand still while the counter frame moves. During the forward movement of the bar thus operated, the pallet bar 16 is also drawn forward by reason of the link 95 13 that connects it to the indorsing bar 11. In this way the movement of the pallet bar 15 is communicated to the pallet bar 16. The pallet bars shown in Fig. 3 are provided with a double ended spring, the outer 100 end 17 of which bears against the adjacent counter channels and holds the pin 14 in engagement with its pallet bar. The other end of the spring 18 embraces between it and the link 13 the indorsing bar 11. A 105 pin 19 carried on the link 14 passes through

the hole 12 in the indorsing bar. The spring 18 prevents this engagement from breaking loose. To get this indorsing bar into position it is inserted between the knurled 5 wheels of one counter channel and the side of the next counter channel, sufficient space being left between them to permit this. It may also be inserted from below the counter frame and between it and the key board of 10 the machine, but I prefer to insert it directly between the two counter channels as above described. To support the indorsing bars I rivet to the bottom end thereof a bracket 20 which rests upon the bottom plate 15 4 of the counter frame. This bracket extends through between the counter channels and has a sufficient bearing space between them to prevent the bar 11 from turning when it is being operated. The outer end of this bracket 20 may be upturned as 20 shown in 21 to make a suitable handle by means of which it may be the more conveniently placed in position between the counter channels.

25 From the above it will be seen that if any two counter actuators are connected up by my improved indorsing bar, and one of them is driven to operate its counter, the other counter actuator will in turn be driven to operate its counter as well. And it will also be noticed that the adjacent counter channels will act as guides for the indorsing bar that is placed between them. In this way the indorsing bar operates as a lever of the third 30 class, the power always being exerted on it between the weight and fulcrum. The pallet bar that is directly driven by the machine is the power of the indorsing bar, the pallet bar that is driven is the weight, and the bar 35 4 or 5 is the fulcrum of the lever in any case. If three or more pallet bars are connected up to the indorsing bar, it may happen that the pallet bar that drives the indorsing bar may be between the other two, in which case

the relation of the parts would vary from 45 that stated above.

Having thus described my invention, what I claim as new and patentable is as follows:

1. The combination in a voting machine of a pair of counter channels, counters and counter actuators supported thereon, a bar 50 extending parallel therewith and guided thereby, connections between selected ones of said actuators and said bar, a stop for limiting the movement of each end of said bar 55 whereby when one of said selected actuators is operated, the said bar, its stops and its connections with the actuators will cause the operation of the other actuators connected thereto.

60 2. In a voting machine, the combination of counters and counter actuators of an indorsing device therefor for causing the simultaneous operation of a plurality of selected ones of said counter actuators consisting of 65 a bar mounted for sliding operation, connections between said bar and said selected counter actuators, and stops for limiting the movement of each end of said bar.

70 3. The combination of an indorsing bar 75 operating as a lever of the third class, two fulcrums around either of which it may rotate, two counter actuators connected thereto by either of which it may be operated against the adjacent fulcrum.

75 4. The combination of an indorsing bar operating as a lever of the third class, two fulcrums around either of which it may rotate, two counter actuators connected thereto by either of which it may be operated to 80 drive the other actuator by rotating said bar around one of said fulcrums.

In testimony whereof I affix my signature in presence of two witnesses.

ALFRED J. GILLESPIE.
